UNITED STATES PATENT OFFICE.

JOHN EDWARD OGDEN, OF CORNWALL, NEW YORK

SINGLE-SECTION-STRUT-SUPPORTED DOOR.

1,274,755.

Specification of Letters Patent.

Patented Aug. 6, 1918.

Application filed August 1, 1917. Serial No. 183,899.

To all whom it may concern:

Be it known that I, JOHN EDWARD OGDEN, a citizen of the United States of America, and a resident of Mountainville, town of 5 Cornwall, Orange county, and State of New York, United States of America, have invented certain new and useful Improvements in Single-Section-Strut-Supported Doors, of which the following is a specification, reference being had to the accompanying drawings, forming a part thereof.

My invention relates to new and useful improvements in doors and especially to such as are adapted to close large openings 15 such as those in pier sheds, warehouses, and the like, and its object is to provide a single section strut supported door of simple construction which shall be easy to operate.

Another object is to so construct the parts 20 that during the operation but little clearance is necessary.

Another object is to so construct the parts that the door section need not be pivoted at points materially above the opening and to 25 so construct and proportion the parts that the struts will firmly support the door section in its raised or open position without obstructing the door opening.

In order that my invention may be thoroughly understood I will now proceed to 30 describe the same in the following specification and then point out the novel features thereof in appended claims.

Referring to the drawings:

Figure 1 is sectional side elevation of a 35 door made according to and embodying this invention with the parts shown in broken lines in their raised or open position.

Fig. 2 is a similar view of a door of modified form of construction.

Like characters of reference designate corresponding parts in all the figures.

10 designates one of the side frames of a door opening and 11 its lintel. The door section 12 is pivotally supported at the part of 45 the door frame by hinges 13 and extends down to the floor 14. Pivotally connected with the vertical edges of the door section at 15 are struts 16 in the lower ends of which 50 are rollers 17. These run in substantially vertical guides 18 which in the arrangement shown in Fig. 1 are on the outside of the building at the sides of the door opening.

Hoisting chains 20 are affixed to the 55 struts—preferably near the rollers 17. These chains run up and over pocket sheaves 21 on

a transverse shaft 22 and down to counterweights 23 which may be placed conveniently within the door posts 10 as shown. 24 designates a hoisting mechanism which comprises a hand chain 25 by means of which the sheaves 21 may be rotated. 26 is a cover to protect the sheaves 21 from the elements.

When the sheaves 21 are rotated the rollers 17 will be raised in guides 18. The pivotal connections 15 are offset from the rollers so that the upward thrust on the struts obtained by this movement will force the door section outwardly and cause it to swing about the hinges 13 until it has reached a 70 substantially horizontal position, as shown by the broken lines. In this position the struts are in position to serve as braces for the door section to hold it firmly and securely in such a position that it acts as a 75 canopy over the door opening. The struts are beyond the side posts of the door opening so they do not obstruct the opening.

A reversal of the operation just described will close the door.

In the arrangement shown in Fig. 2 the roller guides 18^A are at the sides of the door opening inside of the building. They do not as in the structure shown in Fig. 1, extend below the level of the floor 14. In 85 this case it is desirable to have the pivotal connections between the struts 16 and the edges of the door section somewhat above the center of the door section so that when the latter is raised as shown in broken lines, the 90 struts will assume an oblique angle and thus securely brace the door section.

What I claim is:

1. A door section hinged at the upper edge of a door opening, brackets at the edges thereof, downwardly extending struts having their upper ends pivoted to said brackets, means for guiding the lower ends of the struts in a substantially vertical direction, the pivotal connection of the upper ends of 100 the struts with the brackets being offset from said guiding means, hoisting mechanism, flexible elements connecting said hoisting mechanism with the lower parts of the struts, said struts being arranged to support 105 the door section in its swung position without obstructing the door opening.

2. A door section hinged at the upper edge of a door opening and arranged to swing outwardly, outwardly projecting 110 brackets at the edges thereof, downwardly extending struts having their upper ends

pivoted to said brackets, vertical guides for the lower ends of the struts, extending below the door opening, the pivotal connection of the upper ends of the struts with the 5 brackets being offset from said guides, hoisting mechanism, flexible elements connecting said hoisting mechanism with the lower parts of the struts, said struts being arranged to support the door section in its

swung position without obstructing the door opening.

In witness whereof I have hereunto set my hand this 30th day of July, 1917.

JOHN EDWARD OGDEN.

Witnesses:

I. B. MOORE,
WILLIAM G. DALTON.
